UNITED STATES PATENT OFFICE.

CHARLES D. GOLDEN, OF CHICAGO, ILLINOIS.

DESIGN FOR A CIGAR-LIGHTER.

SPECIFICATION forming part of Design No. 26,672, dated February 23, 1897.

Application filed January 16, 1897. Serial No. 619,495. Term of patent 3½ years.

To all whom it may concern:

Be it known that I, CHARLES D. GOLDEN, a citizen of the United States, residing at Chicago, in the county of Cook and State of Illinois, have invented and produced a new and original Design for Cigar-Lighters, of which the following is a specification, reference being had to the accompanying drawing, embodied in a single figure, showing a front elevation in relief of a cigar-lighter illustrating my design.

The principal feature of my design consists of a clock-face surrounded by a wreath of tobacco-leaves, beneath which in bas-relief are the figures symbolizing the presentation of the tobacco-plant by the Indian to the white man.

Referring to the drawing, *a* represents the main feature of my design, upon which is formed in bas-relief three figures—viz., upon the left an Indian girl, in the center a white man, and upon the right an Indian chief. The Indian girl is represented as presenting the tobacco-plant to the white man, who extends one hand to receive it, while with the other he grasps a staff surmounted by a liberty-cap. The Indian chief is in a sitting pos-

ture. In his left hand he grasps a bow and arrows, while in the right hand is a tobacco-pipe. His head is ornamented with eagle-plumes. Between the white man and the maiden is an eagle standing erect upon the ground with a shield upon his breast. Above the three figures described in the central space is represented a clock-face *b*, which is surrounded by a wreath of tobacco-leaves *c*. Upon the left of the main structure is shown a lamp-reservoir *d*, ornamented with a basket-work pattern in intaglio. Above is shown the usual lamp burner and globe *e*. Upon the left and adjacent to the lamp-reservoir is shown an alcohol-cylinder *f*, having a lighter therein with an ornamental handle *g*.

I claim—

The design for a cigar-lighter, substantially as shown and described.

In testimony whereof I have signed this specification, in the presence of two subscribing witnesses, this 23d day of December, 1896.

CHARLES D. GOLDEN.
